DESIGN FOR A HAND TRUCK

George P. Morse and Louis Lidsky,
Brooklyn, N. Y.

Application January 8, 1934, Serial No. 50,353

Term of patent 14 years

To all whom it may concern:

Be it known that we, George P. Morse and Louis Lidsky, citizens of the United States and residing at Brooklyn, in the county of Kings and State of New York, have invented a new, original, and ornamental Design for a Hand Truck, of which the following is a specification, reference being had to the accompanying drawing, forming part hereof and in which the figure is a perspective view of a hand truck showing our new design.

The hand truck of the present design is characterized by an elongated slender shank merging at its upper end into a flat topped triangular handle and at its lower end into legs diverging at

approximately the same angle as the lower angle of the triangular handle, the lower extremities of the legs extending forwardly and resting upon an axle member of the same cross-sectional shape as the legs, and thin, plate-like wheel guards rising from the forward extensions of the legs, including vertical portions lying adjacent the inner faces of the truck wheels and lateral extensions of reduced width overlying the tops of the wheel peripheries.

We claim:

The ornamental design for a hand truck substantially as shown and described.

GEORGE P. MORSE.
LOUIS LIDSKY.
